BOOTH SEAT

Lawrence M. Michelson, Clayton, Mo., assignor to
Duro Chrome Corporation, St. Louis, Mo., a corporation of Missouri

Application February 19, 1948, Serial No. 144,615

Term of patent 14 years

(Cl. D15—11)

To all whom it may concern:

Be it known that I, Lawrence M. Michelson, a citizen of the United States, residing at Clayton, county of St. Louis, State of Missouri, have invented a new, original, and ornamental Design for a Booth Seat, of which the following is a specification, reference being made to the accompanying drawing, forming a part thereof, in which Figure 1 is a front perspective view of a booth seat embodying my new design; Figure 2 is a side perspective view thereof; and Figure 3 is a top plan view thereof.

I claim:

The ornamental design for a booth seat, substantially as shown.

LAWRENCE M. MICHELSON.
